UNITED STATES PATENT OFFICE.

WILLIAM F. HOSFORD, OF OAK PARK, ILLINOIS, ASSIGNOR TO WESTERN ELECTRIC COMPANY, INCORPORATED, OF NEW YORK, N. Y., A CORPORATION OF NEW YORK.

MACHINE FOR METAL-WORKING.

1,298,718.

Specification of Letters Patent.

Patented Apr. 1, 1919.

Application filed November 27, 1916. Serial No. 183,606.

To all whom it may concern:

Be it known that I, WILLIAM F. HOSFORD, a citizen of the United States, residing at Oak Park, in the county of Cook and State 5 of Illinois, have invented certain new and useful Improvements in Machines for Metal-Working, of which the following is a full, clear, concise, and exact description.

This invention relates to a machine for 10 metal working, and more particularly to a machine of this type, such as a punch press or heading machine, in which the metal is subjected to an improved process of electrical heating preparatory to hot pressing.

15 The art of forming metals in punch presses and heading machines was materially broadened when it developed that the process of hot pressing was practicable. Thus by utilizing the method of hot pressing, in which the metals are heated just prior to the forming operation to increase 20 their plasticity, it was made possible to form intricate shapes in one or two forming operations; whereas the same shapes for cold 25 drawing or heading required an extended series of operations, by means of which the metal would be gradually drawn into the shape desired. However, the method of 30 hot pressing has been rather slow in its development due to the difficulties encountered in heating the metal parts prior to pressing. This operation is ordinarily performed by heating the metal blanks in a furnace separate and distinct from the heading 35 machine or punch press and then transferring the heated blank with a pair of tongs from said furnace to the machine. Such a process is necessarily slow and difficult of performance.

40 One object of this invention consists in the production of an improved machine for the electrical heating of the metal just prior to the forming operation. Said machine comprises improved means to automatically 45 feed, cut, heat, and form the metal whereby hot pressing may be placed on the same practical basis now universally employed in cold metal forming and drawing operations.

This and other objects will become ap-

parent from the following description and 50 the appended claims.

The invention is illustrated in the accompanying drawings in which:

Figure 1 is a plan view of the complete 55 machine;

Fig. 2 is a plan view of a portion of the machine partly in section;

Fig. 3 is a vertical section on the line 3—3 of Fig. 2 looking in the direction of 60 the arrows;

Fig. 4 is a vertical section on the line 4—4 of Fig. 2 looking in the direction of the arrows; and

Fig. 5 is an enlarged view of the transfer 65 finger mechanism.

The preferred embodiment of the invention as illustrated in the drawings shows a standard form of heading machine in which a roll of wire is automatically fed to the machine and formed into the particular shape 70 desired. It will be evident, however, that the invention can be readily applied to any kind of metal working machine, such as punch presses, etc., in which the heating of the metal just prior to the forming operation 75 is desirable.

The machine as illustrated in the drawings comprises a base 10 on which are mounted the bearings 11 and 12 and in which is journaled the crank shaft 13. 80 Mounted on the crank shaft 13 is the double crank 7, the cam 6, the fly wheel 14, the cam surfaces 5, 15, and 16, and the wheel crank 17. The crank shaft 13 also carries the crank actuated link 18 which 85 brings the two pivoted parts 8 and 9 of a toggle mechanism into a straight line twice during each revolution of said crank shaft, thereby striking two blows for each revolution of said shaft. The operation of 90 the toggle press is well known in the art and will, therefore, not be described.

Connected to the forward element 9 of the toggle mechanism is the movable ram 19 which serves to actuate the heading punch 95 20. The ram 19 reciprocates to and fro on suitable guide plates secured to the inner side of the lateral supports 23 and 24 of

the base plate 10 and is protected by the cover plates 21 and 22. The machine is fed from a coil of wire, not shown, the wire being guided through feed rolls such as 25 5 and thence through the frame work of the machine, from where it passes through the cut-off quill 26. Secured to the right side of the machine is the bracket 27 in which the slide 28 is reciprocated by means of the connecting rod 29 secured to the wheel crank 17. The slide 28 contains a cam groove 30 in which a roll 31 is fitted, said roll 31 being rigidly secured to the cross slide 32. Consequently as the slide 28 is reciprocated to 10 and fro, the cross slide 32 will be given a lateral motion which is imparted to the cut-off or shearing knife 33 located at the end of the cutter bar 34. A ratchet feed, not shown, operated by the eccentric 6 and the 15 rod 4 steps the roll 25 forward for each revolution of the shaft 13 to advance the wire through the cut-off quill 26 to the feed stop 35, after which the cut-off knife 33 is advanced in the manner just described, 20 severing the wire but retaining it on the cut-off blade by means of a spring transfer finger to be described hereinafter.

Loosely and slidably fitted in a bracket 37 secured to the cover plate 22 is an arm 36 30 which is fitted at its rear end with a pin that rides in a cam slot in the side of the cam 15. This arm 36 and its associated cam 15 serve to move the heading punch 20 vertically, so that the two movable dies 40 and 41 may be 35 brought into proper alignment with the stationary die 42 for the two blows of the ram resulting from each revolution of the crank shaft 13.

A rod 43 secured to the cover plate 21 by 40 brackets 44 and 45 carries one terminal 46 of the electrical heating mechanism. The rod 43 is spring-pressed against the surface of the cam 16 by means of the spiral spring 47. The cam 16 is so designed that it will 45 press the rod 43 forward to hold the blank 48 between the electrical terminals 46 and 49 of the heating element when said blank is transferred from the cut-off quill by means 50 of the cutter 33 and the transfer finger as hereinafter described. A spiral spring 50 serves to interconnect the two sections of the rod 43 and functions to limit the pressure exerted by the heating terminal 46 in the 55 operation of holding the blank 48 between the two terminals 46 and 49 of the electrical heating mechanism.

The method of transferring the wire from 60 the cut-off quill 26 to the heating terminals 46 and 49 is illustrated in detail in Figs. 4 and 5. As the knife 33 advances and severs the wire, the portion cut off is retained on the cut-off blade by means of a spring finger 51. The purpose of the finger 51 is to back up the cut-off blade when severing the wire

and to assist in transferring the blank to the heating terminals. The transfer mechanism, as indicated in Fig. 5, consists of a carrier 52 pivoted and actuated by an end bracket 53 which is bolted to the end of the cut-off slide 32. At the operating end of the carrier 52 is pivoted an arm 55 which is normally kept in its uppermost position through a spring encircled arm 56, said arm being slotted at the upper end so that the arm 55 is free to move up or down. The finger 51 is the active part of this transfer mechanism and when the wire emerges from the cut-off quill 26 this finger is on the opposite side of the cut-off blade, being held there by the pressure of the spring encircling the rod 56. As 70 the cut-off blade 33 advances, the wire is held against deflection at its outer end under the cutting pressure and is held perfectly square while the cut is being made. As the cut-off blade 33 advances with the blank toward the 75 heating terminals the transfer mechanism also advances and carries with it the blank securely held against the end of the cut-off blade 33 by means of the finger 51. The cut-off blade 33 and the finger 51 will thus carry 80 the blank to a position between the heating terminals 46 and 49. When the blank 48 is moved into position between the heating elements by the transfer finger 51, the rod 43 is pressed forward by the action of the cam 95 16 and the blank 48 is rigidly held in position between the heating elements 46 and 49 under the compression of the spring 50 and against return movement from these terminals by a shoulder provided therefor on each 100 one thereof, as clearly indicated in Fig. 2. The pressure exerted by the rod 43 will insure good electrical contact between the terminals 46 and 49 and the ends of the blank 48. After a blank has been moved into this 105 position and is held therein, the cut-off slide 34 returns and the finger 51 of the transfer mechanism snaps back over the wire and is carried back up against a new length of wire 110 which is advanced through the cut-off quill 26.

Secured to the cut-off slide 34 is a second transfer finger 60. This finger is pivoted at 115 61 and is equipped at its operating end with a bifurcation consisting of the rigid finger 62 and the leaf spring finger 63, between which the blank 48 will be rigidly held by the spring 63 when the blank is pushed into place between said fingers. Since the carrying arms 51 and 60 are both secured to the 120 cut-off slide 34 they will reciprocate to and fro in synchronism, and they are so located with respect to the cut-off quill 26 and the heating terminals 46 and 49 respectively that the finger 51 will transfer the blank from the 125 cut-off quill to the heating terminals at the same time that the transfer finger 60 is transferring the blank from the heating terminals

- to the operating dies. When the blanks have been placed in their respective positions the transfer fingers 51 and 60 will snap back over the blanks in their return movement.
- 5 The transfer finger 60, as clearly shown in Figs. 2 and 3, will move the blank 48 into position in front of the stationary die 42 where the blank will be formed into the desired shape by the blows struck by the movable dies 40 and 41 and during a portion of which period the knife 33 will cut off another blank from the feed wire and another blank will be submitted to the heating operation preparatory to forming.
- 10 15 When the blank has been formed to the desired shape by the dies 40, 41, and 42, the knock-out pin 65 operated by the rod 66 pivoted at 67 and controlled by the rod 67' connected to the cam 5 will be moved forward 20 to displace the finished article from the stationary die 42. During the period that the pin 65 is moving forward the transfer fingers 51 and 60 are moved laterally by the cut-off slide 32, transferring the blank contained 25 between the heating elements to the forming dies and the blank just previously severed from the wire to the heating terminals.
- 25 The blank 48 is heated by insertion in a circuit of extremely low resistance and heavy current carrying capacity, the amperage of the current carried by the circuit depending upon the size of the part to be heated and the amount of heat desired. This circuit 30 includes the secondary 68 of a transformer 74, the terminals of which are wired by means of heavy copper leads 69 and 70 to the copper collars 71 and 72 connected respectively to the heating terminals 49 and 46. The terminals 49 and 46, as shown in Fig. 2, are embedded in electrical insulation, such as fiber or rubber, to insulate the heating circuit from the machine proper. The primary 73 of the transformer 74 is adjustable 35 so that the amount of current flowing in the secondary circuit may be readily controlled by primary coil adjustment; the terminals of the primary 73 being connected to a suitable rotary switch 76 mounted on the shaft 13. This switch 76 is designed so that the period during which the circuit of the primary is closed may be controlled by an adjusting screw 75, the operating elements of the switch which close the circuit being 40 mounted on the shaft 13. This switch may be of any suitable design in which the period during which the switch is closed may be readily timed, and in which means are provided for a quick make and break of the circuit, so that the period during which the blank 48 is being heated between the heating terminals 46 and 49 can be accurately controlled. In the preferred form of the invention a switch such as is described in
- my co-pending application, Serial Number 65 52,514, filed Sept. 24, 1915, is used. The switch is connected to any suitable source of power such as the generator 88.
- 5 In order to prevent over-heating of the machine elements in which the blank is heated and formed, the dies 40, 41, and 42 and the heating terminals 46 and 49 are water cooled. As indicated in Fig. 2, the dies 40 and 41 are surrounded by the water cooling chamber 76', and the die 42 by the 75 water cooling chamber 77, these chambers being fed with circulating water by the flexible hose connections 78 and 79 respectively. The heating terminals 46 and 49 are surrounded by the water cooling chambers 80 80 and 81 respectively, which chambers are connected to the flexible hose connections 82 and 83 respectively, by means of which the water is continually circulated around the outer periphery of the heating terminals, the 85 flow of the water being controlled by a suitable valve so that the temperature rise of the terminals is under control.
- 20 The operation of the machine is as follows: 90
- In the following description of the machine it will be assumed that a blank has just been formed and ejected from the stationary die 42 in which condition the various operating elements of the machine will be in 95 the position as indicated in Fig. 1. Under these circumstances a length of wire will have been fed through the cut-off quill 26 and a blank such as 48 will be held in position between the heating terminals 46 and 100 49. With these conditions prevailing, any further movement of the crank shaft 13 will cause the roll 31 to advance in the cam slot 30, and this will start the cross slide 32 in its lateral motion. This movement of the 105 cross slide will advance the cutting bar 34 and the shearing knife 33 which carry with them the transfer fingers 51 and 60. As the shearing knife 33 advances it severs the wire, and said knife in combination with the 110 transfer finger 51 will move the severed end of the wire toward the heating terminals. At about this time, depending upon the temperature rise desired for the blank, the contacts in the switch 76 will be closed, thereby 115 causing a flow of current through the secondary winding 68 of the transformer 74 which includes the blank 48 held between the heating terminals. The current will be permitted to flow in this secondary circuit 120 until the blank has been heated the amount desired, and just prior to the time that the transfer finger 60 grasps the heated blank the circuit of the primary 73 will be opened in the switch 76 and the current flow in the 125 secondary circuit will be interrupted. The switch 76 consequently serves to close the heating circuit after the blank has been

properly inserted in place and a good electrical contact is established between the blank and the heating terminals and also to break this circuit before the blank is removed from 5 said terminals. This arrangement eliminates all possibility of sparkling.

As the cutter bar 34 advances in its lateral movement the bifurcated fingers of the transfer finger will move into the path of 10 the heated blank 48 and said blank will be securely held between said fingers by the action of the finger spring 63. As the transfer finger 60 grasps the heated blank 48 the cam 16 will move to a position so as to retract the rod 43 and hence the heating element 46, thus releasing the blank 48 for lateral movement. The cutter bar 34 will continue to move until it reaches its extreme left position, at which time the heated blank 48 20 will be in direct alinement with the stationary die 42, and the severed blank held between the shearing knife 33 and the transfer finger 51 will be in alinement with the slots in the heating terminals 46 and 49. 25 Further revolution of the crank shaft 13 will then move the ram 19 forward and this will advance the movable dies 40 and 41. At the same time the rod 43 will be moved forward under the influence of the cam 16, which 30 movement will rigidly position the blank held between the shearing knife 33 and transfer finger 51 between the heating terminals 46 and 49. As the ram 19 continues to move forward, the movable die 40 will strike 35 the blank 48 held in the transfer finger 60 and will push it into place in the stationary die 42, thus pushing back the ejecting pin 65 which is free to return to normal because the cam 5 has been turned by the shaft 13 to 40 such a position that the lever 66 and the rod 67' are also free to return to their normal positions.

The action of the movable die 40 upon the blank 48 will depend upon the distance 45 which it protrudes from the heading punch 20, and by properly regulating this distance the die 40 may be utilized to merely insert the blank 48 in the stationary die 42, or to perform in addition to this an upsetting 50 operation.

As soon as the blanks have been rigidly placed in position between the heating terminals 46 and 49 and the dies 40 and 42, the cutter bar 34 will begin to move back to normal, due to the movement of the reciprocating slide 28. In this movement the cutter bar will carry with it the transfer finger mechanisms, the finger 51 snapping over the blank held in position between the heating 55 terminals and the transfer finger 60 pulling away from the blank which is held between the dies and likewise snapping over the blank held between the heating terminals. The toggle movement of the press will now

65 pull back the ram 19, and during this movement the rod 36 under the control of the cam 15 will shift the heading punch 20 so that the movable die 41 will be in direct alinement with the stationary die 42. Under the influence of the toggle mechanism the ram 70 will now again be moved forward and the blank will be formed in its final shape between the dies 41 and 42. The ram will then again be retracted and the ejecting pin 65 under the control of the cam 5 will come forward 75 to knock out the finished part, after which the cycle of operation as above enumerated will be repeated.

The invention as herein described is exceedingly efficient and useful in the production 80 of irregularly shaped articles and will produce the same with a very great degree of accuracy and very rapidly. It will be evident that the invention may be applied to any type of mechanism in which it is desired 85 to form exceedingly complicated and irregularly shaped articles and that the invention is not restricted to the specific embodiment hereinbefore described, but is capable 90 of many variations and applications, without departing from its spirit and scope, as set forth in the appended claims.

What is claimed is:

1. In a device of the character described, the combination with a stationary and movable die, of electrical terminals for heating a blank prior to forming it in said dies, a secondary circuit including said terminals, said circuit being completed by said blank, a primary circuit for energizing said secondary circuit, and a switch associated with said primary circuit whereby the completion of said primary circuit will be properly timed to prevent the flow of current in said secondary circuit when the blank is being inserted or removed from said terminals. 95 100 105

2. In an electric heating device for hot pressing, the combination with a stationary and a movable terminal, a secondary heating circuit including said terminals and said blank, means actuated to operate said movable terminal, means to deposit the blank between said terminals, a primary circuit for energizing said secondary circuit, and switching means associated with said primary circuit whereby the time of current flow and the time at which said primary circuit shall be opened and closed can be automatically controlled. 110 115 120

3. In a device of the character described, the combination with a stationary and movable die, of means for feeding a strip of metal to the machine, means for cutting blanks from said strip, electrically operated means including heating terminals for heating 125 said blanks, positively operated means for transferring said blanks from said cutter to said terminals, and means for trans-

ferring the heated blank from said terminals to said dies.

4. In a device of the character described, the combination with a stationary and movable die, of means for feeding a strip of metal to the machine, means for cutting blanks from said strip, means for heating said blanks, means for transferring said

blank from said cutter to said heating means, and positively operated means for 10 transferring the heated blank from said heating means to said dies.

In witness whereof, I hereunto subscribe my name this 20th day of November A. D., 1916.

WILLIAM F. HOSFORD.
